UNITED STATES PATENT OFFICE

THOMAS O'CONNELL, OF ST. PAUL, MINNESOTA

RADIATOR HANGER

Application filed May 26, 1930. Serial No. 455,505.

The present invention relates to a wall radiator hanger.

Various types of wall supports for radiators have been devised to hold a radiator in position without the necessity of using supporting legs on the floor over which the radiator is mounted. It is necessary when mounting a radiator to space the radiator a required distance above the floor and to space it outwardly from the wall against which it is mounted. Most of the radiator hangers at present in use have a portion thereof adapted to receive a transverse radiator element thereon such as the connection between adjacent sections or the connection between columns in the same section.

An object of the present invention is to support a radiator by means engaging a vertical radiator element.

These and other features of the invention will be more fully brought out in the following description and the accompanying drawings, wherein:

Figure 1 is a view in vertical transverse section through a radiator supported by a hanger embodying the present invention.

Figure 2 is a sectional view on the line 2—2 of Figure 1, showing the rear face of the supporting plate.

Figure 3 is a sectional view on the line 3—3 of Figure 1.

Figure 4 is a view in side elevation of a hanger positioning element.

Figure 5 is a view in top elevation of the device shown in Figure 4.

Figure 6 is a view in top elevation of a bottom spacing member to hold the radiator spaced outwardly from the wall; and

Figures 7 and 8 show, respectively, in perspective the inner and outer composite parts of the spacing member which is shown assembled in Figure 6.

Referring to the drawings in detail, a supporting plate 1 is of heavy sheet metal, such as boiler plate, having an outwardly bent portion 2 at the end thereof and an upwardly bent flange 3 to support a radiator engaging member. The radiator engaging member comprises a plate 4, also of heavy sheet metal, having a downwardly bent flange 5 at the

inner or rear end thereof and having a pair of openings in the horizontal portion thereof which receive the upwardly bent ends 6 and 7 of a U-shaped rod 8 which encircles a radiator column 9.

The wall plate 1 is provided with an enlarged opening 10 of a size to receive the head of a lag screw 11 which enters the wall to support the plate 1. An offset portion 12 is provided in the upper edge of this enlarged opening of a size to engage the shank of the lag bolt 11. Spurs 14 are cut from the metal of the plate 1 and bent to lie perpendicularly to the face of the plate 1. These spurs or points are adapted to be driven into the supporting wall to anchor the plate in position thereon.

A band 15 of strap metal is formed to encircle the radiator or column below the radiator hanger to prevent downward slippage of the U-shaped rod 8 in case the radiator is moved upwardly so as to take the weight of the radiator off the hanger. An outwardly bent portion 16 of this strap member is adapted to support the U-shaped rod 8. The strap 15 is provided with outwardly bent end portions 17 and 18, each of which is provided with an opening to receive a bolt 19 to secure the strap in position. The particular structure of this supporting member is not material as any device which would support the U-shaped rod 8 against downward displacement would be suitable.

A foot spacing member 20 comprises a transverse narrow outer portion 21 having a downwardly bent flange thereon, this outer portion being wide enough to extend transversely between two adjacent sections of the radiator. The downwardly bent flange is shaped to enter the space between adjacent columns in each of the sections to hold the device in a horizontal position, as shown in Figure 1. The shank portion 22 of the outer composite member is provided with a plurality of openings 23 of a size to receive a bolt 24. The inner or rear portion comprises a shank 25 having downwardly bent flanges 26 and 27 on each edge thereof to form a recess in which the shank portion 22 of the outer member is free to slide. An opening 28

is provided in the inner or rear member 25 to receive a bolt 29. The inner or rear end of the rear member 25 is bent downwardly to provide an enlarged area to engage the surface of the supporting wall.

In using the device, the wall plate 1 is secured in position on the wall by the lag screw 11 at approximately the required height and the spurs 18 are driven into the wall. The 10 U-shaped rod 8 is then passed around the column of the radiator and the upwardly bent end portions 6 and 7 thereof are inserted through the openings provided therefor in the plate 8. Nuts 30 and 31 are then threaded onto the end of the rod 8 to hold it securely in position in the plate 1. The rod supporting member 15 is then secured in position around the radiator column by means of the bolt 19. The foot spacing member 20 is then 15 inserted vertically in the space between two adjacent sections of the radiator and is turned to a horizontal position, as shown in Figure 1, so that the transverse outer portion 21 thereof is positioned in the space between columns of the sections, as shown in Figure 1. The length of the member is adjusted by inserting the bolt 29 in the proper openings 23 in the forward member 22 and the bolt is tightened to securely lock the parts 20 in adjusted position.

The radiator is then lifted into position as shown in Figure 1 with the downwardly bent flange 5 of the plate 4 engaging the upwardly bent flange 3 of the wall plate 1. The 25 point of engagement of the plate 4 with the wall plate 1 forms a fulcrum from which point the plate 4 by its own weight pivots downwardly so that the rod 8 engages the forward surface of the rear radiator column around which the rod 8 is positioned. As the radiator is released the rod 8 engages the forward edge of the rear column 9 and the plate 4 engages the rear surface of the column 9. The sharpened forward 40 edge of the plate 4 bites into the metal of the column and prevents downward slippage of the radiator, securely mounting the radiator in position.

Should the pipes which run to the radiator 50 expand to such point as to raise the radiator somewhat, the U-rod supporting member 15 would prevent the U-shaped rod 8 from slipping downwardly so that upon cooling again the radiator would move downwardly again to its original position and the plate 4 would engage the column 9 at its previous position. The probability of the radiator ever being 55 actually raised by the supply pipes therefor is remote, but this action may occur with certain installations and it is desirable to provide for such contingency. The position of the U-bolt member and plate 4 is determined by the position of the U-bolt supporting member 15 on the column and the position of the 60 U-bolt supporting members may be readily

changed by means of a screw driver or other instrument inserted between the columns of the radiator.

I claim:

1. A radiator hanger, comprising a wall element having an upwardly projecting flange thereon, a radiator supporting plate supported by said wall element and adapted to engage the rear face of a radiator element, and a U-bolt adapted to encircle said radiator element to have interlocking engagement with said radiator supporting plate to bind the radiator element against downward displacement. 75

2. A radiator hanger, comprising a wall element, a radiator supporting member having interlocking engagement with said wall element, a U-bolt surrounding a radiator element to hold said radiator element against an edge of said radiator supporting member to clamp said radiator element against downward displacement. 80

3. A radiator hanger comprising a supporting member fixedly secured to a wall and having a horizontal supporting surface parallel to said wall, a radiator supporting member having interlocking engagement with said supporting surface and free for 90 slidable movement longitudinally thereof and free for pivotal movement about the upper edge of said surface as a fulcrum, a radiator engaging element secured to said radiator supporting member and spaced therefrom a distance greater than the maximum diameter of a radiator column to be supported thereby, said radiator engaging member engaging a radiator column when moved pivotally downward about said fulcrum to hold said vertical radiator element against the forward edge of said radiator supporting member to bind said radiator element against downward displacement. 95

4. A radiator hanger, comprising a wall element, a radiator supporting element having a sharpened edge portion directed to engage a side of a radiator column and supportingly engaged by said wall element, and means carried by said radiator support member extending around a radiator column to engage the opposite side of said column from that engaged by said edge portion, the normal distance between said edge portion and the portion engaging said opposite side of said column being greater than the maximum diameter of said column the portion 100 engaging the opposite side of said column being adapted to be moved downwardly by engagement with said radiator column to force said edge portion into supporting engagement with said radiator column. 110

5. A radiator hanger, comprising a supporting member fixedly secured to a wall, means adapted to interlock with said supporting member to be supported thereby and to be free for lateral slidable movement. 115

thereon, said means having an edge portion adapted to engage a side of a radiator column, means connected to said first means and extending loosely around a radiator 5 column to engage the opposite side of said column from said edge portion, said opposite engaging means being pivotally movable to bind a radiator column against downward displacement.

10 In testimony whereof I affix my signature.
THOMAS O'CONNELL.
